CLAIM

The ornamental design for a cutting tool, as shown and
described.

DESCRIPTION

FIG. 1 is a front, perspective view of a tool;

FIG. 2 is a front elevational view of the tool shown in FIG.
1;

FIG. 3 is a back elevational view of the tool shown in FIG.
1;

FIG. 4 is a side elevational view of the tool shown in FIG.
1, with the other side elevational view being identical;

FIG. 5 is a top plan view of the tool shown in FIG. 1; and,
FIG. 6 is a bottom plan view of the tool shown in FIG. 1.
The broken lines in the drawings depict unclaimed environmental
subject matter.

Any combination of the illustrated features, including
claimed features and non-claimed features, may be claimed
in this application or a continuing application claiming
priority to this application by converting any portion of the
broken lines to solid lines, any portion of the solid lines to
broken lines, or both.
